UNITED STATES PATENT OFFICE.

GREEN FENTON, OF STREETSBOROUGH, OHIO.

NECK-YOKE.

SPECIFICATION forming part of Letters Patent No. 257,158, dated May 2, 1882.

Application filed November 9, 1881. (No model.)

To all whom it may concern:

Be it known that I, GREEN FENTON, of Streetsborough, in the county of Portage and State of Ohio, have invented a certain new and 5 Improved device for Neck-Yokes and Whiffle-trees; and I do hereby declare that the following is a full, clear, and complete description thereof.

My invention relates to a device or article 10 for neck-yokes and whiffle-trees; and the improvement consists in constructing the article in a conical tubular form of metal, the base or largest diameter of the cone being at or near the point of the pole ring or loop attachment, 15 thence tapering to the ends. The interior of the tube is provided with braces arranged in an angular position and extending through the said tube longitudinally. The central portion of the tube is strengthened by a sleeve or 20 ferrule, to which the pole ring or loop is connected. For a more full and complete description of the said invention reference will be had to the following specification, and to the annexed drawings, making a part of the 25 same, in which—

Figure 1 is a view of the article as a neck-yoke; Fig. 2, a longitudinal section; Fig. 3, a transverse section in the direction of the line $\alpha\alpha$, Fig. 1. Fig. 4 is a longitudinal horizontal section of the sleeve or ferrule. Fig. 5 is a vertical longitudinal section of the said 30 sleeve or ferrule. Fig. 6 shows a modification.

Like letters of reference refer to like parts in the several views.

35 The article may be made by casting it of iron or steel; or it may be formed up of sheet metal. A combination of the two metals is preferable in some cases.

The cone-shaped tubes A B, Figs. 1 and 2, 40 are strengthened by the longitudinal brace C, arranged at right angles, or nearly so, as seen in Fig. 3. This brace is fitted closely to the interior of each section A and B in such manner as to admit of the ends at $\alpha\alpha$ lapping or 45 joining onto each other, there being a tenon or rabbets at the points $\alpha\alpha$, so that one end will be received into the end of the other to admit of the exterior and interior surfaces of the tube being even and smooth, as seen in Fig. 2. The 50 brace is first fitted into one of the sections, and then the other section is fitted over the brace,

lapping on the adjoining section, as before stated. To secure the joint at $\alpha\alpha$, and to give additional strength to the central part of the yoke when it is subjected to the greatest strain, 55 a ferrule, D, Figs. 2 and 3, is next fitted tightly on over the whiffle-tree and secured thereto by means of pins or screws c. On the lower side of the ferrule is a boss, E, in which is a slot, d, Fig. 4, on each side of which is an 60 angular depression, e e, Figs 4 and 5. The slot d extends through the boss and is in a right-angular relation, or nearly so, to the slot. This arrangement of the boss is for receiving and holding the pole ring or loop F, Figs. 1 65 and 2, which is provided with a T-head, as indicated at f, Fig. 2. In connecting the loop with the ferrule the head f is passed from the under side through the slot d, and then by a quarter-turn of the loop the head f will drop 70 into the recesses e e, as indicated in Fig. 2. The loop is connected with the ferrule before it is fitted onto the yoke, which will prevent the head of the loop from being forced up out of the recesses, as the head will be brought in 75 contact with the face or side of the neck-yoke on being raised up, as the recesses are covered over by the whiffle-tree. It will be noted that the outside ends of the recesses are wider than at the junction with the slot, the purpose of 80 this being to admit of the loop turning and hanging loosely in the ferrule, that it may be easily turned or moved to receive the pole, and that it may readily adjust itself to the movements of the strain and motion of the pole. 85

In applying the tubular construction to a double-tree or whiffle-tree it is made in an oval form, as seen in Fig. 6, instead of circular, as shown in Fig. 1, and when made in an oval or compressed shape, as noted, it is strengthened 90 by an interior brace, C', essentially the same as C in Figs. 2 and 3, only at a different angle to suit the oval form, which is made tapering from the central part of the whiffle-tree to the ends, essentially the same as the tapering of the yoke. 95

In adapting the neck-yoke construction to whiffle-trees the form only need be changed from a circular one to an oval one. The construction and arrangement of the several parts may be substantially the same, differing only 100 in their respective forms—as, for instance, in the latter case the ferrule D should be oval instead

of circular, that it may fit to the shape of the whiffletree, &c.

The loop or ring F may be shaped into the form of a clevis, to be attached to the whiffletree 5 or to the double-tree in the ordinary manner.

If preferred, the loop F and the boss E may be entirely dispensed with, and an ordinary strap-loop used in place thereof, by attaching the strap around the ring between the collar 10 at the ends thereof, and in some cases of light construction the braces C may not be required.

What I claim as my invention, and desire to secure by Letters Patent, is—

The sectional tubular neck-yoke A, having the brace C and the lap-joint a, in combination 15 with the ferrule D, having boss E, with slot and groove e e for the reception of the T-headed ring, substantially as set forth.

In testimony whereof I affix my signature in presence of two witnesses.

GREEN FENTON.
